J. O. HOWARD,
TOY AEROPLANE,
APPLICATION FILED JAN. 23, 1919.

1,420,193.

Patented June 20, 1922.

JOSEPH O. HOWARD ^{Inventor}

By *Charles E. Nourse*
Attorney

UNITED STATES PATENT OFFICE.

JOSEPH O. HOWARD, OF DETROIT, MICHIGAN.

TOY AEROPLANE.

1,420,193.

Specification of Letters Patent. Patented June 20, 1922.

Application filed January 23, 1919. Serial No. 272,628.

To all whom it may concern:

Be it known that I, JOSEPH O. HOWARD, a citizen of the United States, residing at Detroit, county of Wayne, State of Michigan,

5 have invented a certain new and useful Improvement in Toy Aeroplanes, and declare the following to be a full, clear, and exact description of the same, such as will enable others skilled in the art to which it 10 pertains to make and use the same, reference being had to the accompanying drawings, which form a part of this specification.

This invention relates to toy aeroplanes, and its object is to provide an aeroplane 15 made of paper, the design and construction being such as to secure the necessary strength and stability for the purpose so that (although the device is made of paper) the several parts of the structure, due to the 20 design and arrangement, are of sufficient strength to prevent distortion or displacement thereof in ordinary use. I am aware that toy aeroplanes have heretofore been made of paper but in such former constructions the device becomes so quickly deformed 25 in use as to be of little service. This invention seeks to avoid such former weaknesses in construction and to provide a device that is adapted to be thrown by hand 30 and, due to the momentum thus acquired, to maintain itself for a period in the air and to simulate an ordinary aeroplane in flight. An additional object of the invention is to provide an aeroplane of a construction in 35 which the center of gravity of the device is positioned forward of the center of lift of the sustaining plane and a permanently positioned elevating plane positioned at the tail of a character tending to depress the tail 40 in flight and to secure an aeroplane that subsequent to its being cast into the air tends to continue in flight through the action of force of gravity as is hereinafter shown.

Another object of the invention is to provide 45 a fuselage or body of a rigid construction in the form of a cone, the upper surface of which is slotted at two spaced points providing means to receive and hold the edges of the plane extending thereacross in the desired curve and angle of incidence necessary for flight. An additional object is to provide a unique landing gear of paper of a shape and character tending to maintain the plane in lateral equilibrium upon striking the surface as the floor. These and other 55 objects and the several novel features of the

invention in its preferred form are herein-after more fully described and claimed and shown in the accompanying drawings in which—

60

Fig. 1 is a plan view of a toy aeroplane embodying my invention.

Fig. 2 is a side elevation thereof.

Fig. 3 is a detail in end elevation showing an alternative form of construction of 65 the plane.

The device is preferably of the monoplane type and the fuselage or body 1 is formed of paper rolled to shape forming a long tapering cone, the body being practically of 70 a single roll with the edges of the paper secured together and providing a body which is very light in weight and of the maximum of strength. The large end of the cone is at the forward end of the body as is shown 75 in the drawing and at the forward end has a cork ballast secured within the interior thereof as indicated by dotted lines 2 in Fig. 2 by means of which the necessary weight at the forward end is secured. The cone 1 80 extends somewhat forward of the front end of the cork member and about this end is wrapped a second cone providing a pointed nose 3 formed of paper and having a trailing portion 4 extending below the under side 85 of the body providing a landing gear, the terminal end of which is bent upward and secured to the lower side of the body as indicated at 5. This portion 4 is somewhat 90 wider than the body at the forward end, as will be understood from Fig. 1, and provides a surface in continuation of and at the same angle as the portion of the cone member 3 of which it forms a part. This landing gear tends to right the plane as it strikes 95 a surface bringing it to rest on the landing gear as the width of the part 4 is such as to hold the device in lateral balance when at rest.

The plane 6 extends transversely of the 100 fuselage, being centrally positioned thereon as shown, and this plane may be formed of a single sheet of paper of desired shape or may be made of a number of sheets as is hereinafter described. In either form of 105 construction, however, the plane is secured to the body in the same manner. For this purpose the body is provided with an angular slit near the forward end providing a flap 7, the angle of this slit quite closely approaching the horizontal. A similar slit is 110 formed toward the rear end of the body pro-

viding a flap 8 and this latter slit is preferably at a greater angle to the horizontal, as will be understood from Fig. 2. The longitudinal edges of the plane are inserted in 5 the respective slits and the distance between the bottom of the two slits is less than the normal width of the plane member, whereby the plane when in position is held in the form of a curve. This curved shape together 10 with the formation of the slits at different angles gives the plane the necessary form and angle of incidence, the entering edge of the wing relative to a horizontal line being higher than the trailing edge. In this respect 15 the plane quite closely approaches the shape in cross section of the commercial aeroplane.

As above stated, the plane may be of a single sheet of paper or it may be of two 20 sheets. If of the latter construction, it is formed of the lower member 9 and the upper member 10 which is bent to a curve slightly somewhat less in diameter than the curve of the lower member 9 and is sustained 25 in such relationship by turning the opposite longitudinal edges 11 of the member 9 over the edge of the upper member 10 as shown in Fig. 3. This provides a plane considerably stiffer than the plane formed 30 of a single sheet and the composite plane thus formed is secured in slits in the body in the same manner as is shown in Fig. 2 providing the necessary form and angle of incidence. The main difference between the 35 two types of planes is that the latter type is of greater strength.

For the purpose of flight the aeroplane is necessarily provided with a vertical and horizontal rudder. These, I have formed 40 of paper and to secure the same to the tail end of the fuselage I provide cross slits in the said tail end, the vertical portion of which is adapted to receive the vertical rudder and the horizontal portion to receive 45 the horizontal rudder which are glued in place. These rudders are fixed as to shape and position so far as the character or material will permit and the horizontal rudder 12, as will be understood from Fig. 2, is 50 provided with a terminal upturned portion 13, the tendency of which in flight is to turn the nose of the device upward so that it tends to traverse the air in nearly horizontal position its upward tendency counteracting 55 the weight at the forward end. The vertical rudder 14 may be of any desired shape tending to maintain the device in flight in a straight line in a horizontal plane.

By the provision of the cork ballast at 60 the forward end, the device may be weighted to a greater or less extent by simply inserting a tack or the like therein and thus the necessary balance of the device may be secured by the addition of a greater or less 65 number of tacks or other devices necessary

to balance the device fore and aft. While I have described a cork ballast and method of attaching weights thereto to secure the necessary balance it is evident that the device may be weighted in any approved manner to secure the desired result. The necessity of weighting the forward end of the fuselage is occasioned by the necessity of providing in a toy aeroplane a "tractor" element. In a commercial aeroplane 75 "tractor" is the propeller which draws the aeroplane forward through the air and in such case the center of gravity may be at or behind what is known as the center of lift of the sustaining plane. In this present invention, even though the device may be cast into the air by hand as suggested, the weight positioned forward of the center of lift of 80 the sustaining plane tends to cause the machine to sail properly.

By the weight being 85 thus forward of the center of lift, gravity has a tendency to turn the machine to a descending angle about a transverse axis at the center of lift. This causes the machine to fall at a descending angle and the acceleration in speed causes the elevating planes (which are permanently upwardly inclined or upturned as shown) to counteract the tendency of the weight to turn the machine downward and causes the same to traverse a 90 nearly horizontal plane. In a toy of the general character shown, if the center of gravity is positioned at or behind the center of lift, the toy would simply fall in a manner similar to a commercial aeroplane in falling out of control. With the center of gravity 95 forward of the center of lift as shown, the device will continue in flight for a distance greater than the force applied alone 100 would impel it due to the action of gravity which causes it to pick up speed and thus make a succession of steps in flight, it starting in a substantially horizontal line then falling for a short distance until speed is attained in which the elevating planes will 105 again turn the machine to horizontal and, upon sufficient decrease in speed, gravity again acts to turn the machine to a descending angle in which speed is increased until the same is again turned to substantially a horizontal plane. Successful and prolonged 110 flight of this device depends upon this feature of construction. From the above description it will be readily understood as to what is meant by the weighting of the nose 115 to a greater or less extent to obtain the necessary balance.

Having thus briefly described my invention, what I claim is—

1. A toy aeroplane comprising a long cone shaped body of paper, a nose member provided at the forward end of the body, the said body having a slit formed therein near the forward end and a second slit toward the rear or pointed end of the body, the slit 125

- at the forward end being at a less angle to the horizontal than the slit toward the rear end, and a plane member the edges of which are inserted in the slits, the distance 5 between the bottom of the slits being less than the normal width of the plane whereby said plane is held in a curved shape in cross section, the flaps provided by the said slits being glued to the plane.
- 10 2. A toy aeroplane comprising a long cone shaped fuselage of paper, a coned nose member thereon, a plane secured to the upper surface, a landing gear formed with a surface coincident with the lower surface of the 15 nose member and extending below the lower side of the body, and a fixed vertical and horizontal rudder at the tail end of the body portion.
- 15 3. A toy aeroplane consisting of a body 20 formed of paper, a plane member of paper extending equidistantly each side of the body, said body being provided with slits near the forward and toward the rear end thereof in which the entering and trailing 25 edges respectively of the plane member may be inserted, the distance between the bottom of the forward and rear slits being less than the normal width of the plane member whereby the same is bowed in cross section 30 in assembling with the body, the entering edge of the plane member being at a greater distance from the longitudinal axis of the body than the trailing edge, and fixed vertical and horizontal rudders at the tail of 35 the body, the horizontal rudder being of a shape tending to cause elevation of the nose in flight.
4. A toy aeroplane consisting of a cone shaped fuselage of paper, a fixed horizontal 40 and vertical rudder secured to the pointed end of the body, a cone shaped nose member secured at the forward end thereof, a plane secured to the upper surface of the body, the body having a slit near the forward end to receive the entering edge of the plane and a slit toward the rear end to receive the trailing edge of the plane, the 45 slits being of a distance apart to hold the plane in curved shape in cross section and 50 the angle of the slits positioning the plane at the desired angle of incidence.
5. A toy aeroplane consisting of a cone shaped fuselage of paper, a coned nose member of paper secured to the large end thereof, fixed horizontal and vertical rudders at the rear end thereof, and a plane member centrally positioned transversely of the body near the forward end, the entering edge of the plane member being at a greater distance from the longitudinal axis of the 55 body than the trailing edge, the plane member consisting of an upper and lower sheet of paper, the upper sheet being curved on a radius of less diameter than the lower sheet spacing the said sheets for the greater 60 portion of their width, the sheets being secured together at the forward and rear edges only, and means on the body for receiving the plane member to maintain the same in bowed form in cross section. 70
6. A toy aeroplane comprising a long cone shaped fuselage formed of a roll of paper, a cone shaped paper nose member secured to the large end of the fuselage and having an integral portion extending beneath the 75 body, the end of said portion being secured to the body to hold said portion in spaced relation therewith and providing a landing gear, the terminal portion of which provides a surface transversely of the body of 80 greater width adapted to sustain the plane in lateral equilibrium when resting on a surface, a plane secured to the upper surface of the fuselage near the forward end, and a vertical and horizontal rudder at the 85 pointed end of the fuselage.
7. A toy aeroplane consisting of a cone shaped fuselage formed of paper, a coned nose member secured to the forward large end thereof, a paper plane member secured 90 near the forward end of the body, a ballast member secured to the large end of the fuselage positioning the center of gravity of the device forward of the center of lift of the plane member and a fixed vertical and 95 horizontal rudder at the small end of the body, the horizontal rudder having an upwardly curved terminal portion tending to guide the device upward when in flight.

In testimony whereof, I sign this specification. 100

JOSEPH O. HOWARD.
